C. H. BOURGEOIS
SWITCH OPERATING MECHANISM

Filed March 25, 1926

UNITED STATES PATENT OFFICE.

CLARENCE H. BOURGEOIS, OF TOLEDO, OHIO, ASSIGNOR TO THE HAUGHTON ELEVATOR & MACHINE COMPANY, OF TOLEDO, OHIO, A CORPORATION OF OHIO.

SWITCH-OPERATING MECHANISM.

Application filed March 25, 1926. Serial No. 97,481.

This invention relates to switch operating devices.

This invention has utility when incorporated in switch re-setting means.

5 Referring to the drawings:

Fig. 1 is a fragmentary view showing an embodiment of the invention in connection with an electric elevator;

Fig. 2 is a fragmentary view of a switch board for the installation of Fig. 1, showing the invention in side elevation;

Fig. 3 is a section on the line III—III, Fig. 2, on an enlarged scale;

Fig. 4 is a section on the line IV—IV, 15 Fig. 3;

Fig. 5 is a section on the line V—V, Fig. 4; and

Fig. 6 is a view looking into the leakage plug from the right of Fig. 4.

20 Electric motor 1 is effective through drum 2 for driving elevator car 3 in shaft 4. This car is suspended by cable 5 extending about the drum 2 and idler 6 to counterweight 7 in the shaft 4. Control board 8 is shown as carrying brackets 9 for shafts 10, 11, 12, as actuated by motors 13, 14, 15. The motor 15 is shown as carrying pinion 16 in mesh with gear 17 on the shaft 12 as carrying cams 18 for rocking arms 19 into and out of contact

25 with terminals 20 and thereby closing and opening switches as remotely determined by controller 21 in the car 3.

The rock shaft 12 has collar 22 mounted thereon with extension 23 swingable in either

30 direction of rotation of the shaft 12 to abut fixed stop 24 and thereby determine the limit of rocking of the shaft 12 to somewhat less than 180° from the downward position of the extension 23 as at the open or inoperative position for the switches 19, 20.

35 From the extension 23 extends chain 25 to eyes 26 of counterweight or piston 27 as guided by cylinder 28 carried by the bracket 9 fixed with the switchboard or panel 8 in coaxial position from the shaft 12 centrally through the downward position of the extension 23. This piston is given weight by having its shell 27, say of iron, loaded with filler

40 29 say of lead. This piston 27 has chamber

45 30 therein for ball 31 as closing port 32 in

55 plug 33 from the lower side of this piston 27. Upwardly from this chamber 30, there is oval vent opening 34. Accordingly, there is provided in this piston, a ball type of check valve permitting the piston 27, as guided by the cylinder 28, having bottom closure or head 35, to descend or fall freely toward such bottom 35 in thus having the centering weight 27, 29, fully effective in resetting or pulling the shaft 12 back to initial or starting position from 60 the position of wrapping the chain 25 upon the collar 22. This recover action is effective as the motor 15 is deenergized, and accordingly through the gearing 17, 16, may effect 65 this idle or recovery resetting rotation.

65 The driving action of the motor 15 for operating the cams 18 and shifting the switches 19 toward switch closing position in the desired sequence for motor acceleration is preferably a somewhat retarded action for this 70 torque motor 15, say as of three-phase alternating current. To bring about such retarded action, the ball check valve in the piston precludes entrance of air and the lifting attempt on the piston 27 by the chain 25 is 75

one opposed by the suction in the lower portion of this piston and cylinder retarding device. The degree of such suction may be nicely adjusted for the desired timing and closing of the acceleration switches for cutting out acceleration resistance in starting 80 the motor 1. This is effected by port 36

85 through lug 37 as spaced from the bottom 35 to extend through the side wall of the cylinder 28 into the region of the piston 27 as in down position and above the bottom of such piston 27. This port 36 has vent 38 adjustable by plug 39 so that after the port 36 is cleared by the piston 27, there may be an adjusted air leakage into the cylinder, thereby to re-

lieve the suction resistance against ascent of the piston 27 while the motor 15 is driving through the gearing 16, 17, for operating the shaft 12 to cause the cams 18 to throw the switch arms 19 into the switch closing positions at the terminals 20 in the predetermined sequence.

90 The position of the port 36, as above the bottom of the piston 27, causes the piston 27 to have a materially increased loading on the 100

motor 15 beyond the gravity load. This insures a snug setting of the ball 31 in closed position. As the piston ascends to clear the port 36, there may be an adjusted slight relief in this suction action for determining the desired timing for the operation of the acceleration switches. As the motor 15 is de-energized, the loaded piston 27 drops rapidly in swinging the rock shaft 12 and the switch 10 arms 19 into switch opening positions. The ball 31 is unseated, and there is free flow of the fluid from the lower portion of the cylinder 28. The oval configuration of the vent 34 precludes lodging of the ball 31 therein 15 so that as the piston 27 has reached its lowest position in such close proximity as to almost abut the head 35 without pounding such head, the ball 31 then is seated and the device is in position for a repetition of the 20 cycle of operations.

An important advantage of the present construction is its reliability in insuring the quick return of the switch by gravity to inactive or off position, as soon as the torque 25 motor is de-energized, and in retaining it in that position regardless of the rapidity with which it approaches such position. The great mass of the piston 27, 29 gives a quick downward pull. The check valve ball 31 30 allows the air to escape freely from beneath the piston and permits the rapid descent of the piston toward the closed end of the cylinder. When the switch reaches its central or off position, the piston is at the lowest point 35 in its movement, and the lug or projection 23 is at its lowermost or dead center position. A comparatively slight upward or return movement of the piston at this time, with the momentum of the rotating parts at a maximum, would therefore permit the rock shaft 40 to continue its movement, and possibly throw the switch into reverse position. It is important, then, to provide means for strongly and instantly resisting the movement of the 45 piston, at the moment it reaches its limiting position. Such resistance is insured by the fact that the piston cooperates with the lower end of the cylinder to form an entirely closed space until the piston is moved upwardly far 50 enough to uncover the leakage port 36. When the piston reaches its lowermost position, there is substantially no air chamber beneath it, and as a consequence, a substantially complete vacuum must be produced in the closed 55 end of the cylinder as the piston moves upwardly. A resistance of substantially 15 pounds per square inch must, therefore, be overcome, in addition to the weight of the piston. This prevents any accidental movement of the switch into reverse position unless the torque motor is intentionally energized by the action of the operator to effect such movement.

What is claimed and it is desired to secure 60 by United States Letters Patent is:

1. The combination with a switch operating rock shaft, of an actuator for the shaft, means retarding the rocking of said shaft when acted upon by said actuator, said retarding means embodying a weight connected to the rock shaft and a guide cooperating with the weight to form a completely closed space during a predetermined fractional part only of the movement of said weight. 70

2. The combination with a switch operating rock shaft, of an actuator for the shaft, means for retarding the rocking of said shaft when acted upon by said actuator, said retarding means embodying a piston connected with the rock shaft and a cylinder in which the piston is guided, said piston cooperating with the end of the cylinder remote from the rock shaft to form a completely closed space during a predetermined fractional part only of the movement of said piston. 75

3. The combination with a switch operating rock shaft, of an actuator for the shaft, means retarding the rocking of said shaft when acted upon by said actuator, said retarding means embodying a piston connected with the rock shaft and a cylinder in which the piston is guided, said piston, when near one end of the cylinder, cooperating with said end to form a completely closed space, said cylinder being provided with a leakage port which is uncovered by the piston only after it has moved an appreciable distance away from said end. 90

4. The combination with a switch operating rock shaft, an actuator for the shaft, means retarding the rocking of said shaft when acted upon by said actuator, said retarding means embodying a cylinder having a closed end portion, and a piston connected with the rock shaft and movable substantially to the extreme end of the cylinder without actually pounding the same, said cylinder having a leakage port at an appreciable distance from said end. 100

5. The combination with a shaft rockable in either direction from a central position, a lug on said shaft which projects downwardly when the shaft is in central position, a piston connected to said lug, a cylinder with which the piston is associated, said piston and cylinder cooperating to form a completely closed space when the piston is in lowermost position, and an upwardly opening check valve in the cylinder to permit the free movement of the piston downwardly. 110

6. The combination with a shaft rockable in either direction from a central position, a lug on said shaft which projects downwardly when the shaft is in central position, a piston connected to said lug, a cylinder with which the piston is associated, said piston and cylinder cooperating to form a completely closed space when the piston is in lowermost position, and an upwardly opening check valve in the cylinder to permit the free movement of the piston downwardly. 120

the piston downwardly, said cylinder having a leakage port in position to be uncovered by the piston only after said piston has moved an appreciable distance away from the end 5 of the cylinder.

7. The combination with a switch operating rock shaft, of an actuator for the shaft, and means for retarding the rocking of said shaft when acted upon by said actuator, said 10 retarding means embodying a piston, a flexible element connecting said piston with the rock shaft, and a substantially vertical cylinder in which the piston is guided, said piston cooperating with the lower end of the cylinder 15 to form a completely closed space during a predetermined portion of the movement of said piston, said piston having a port therethrough provided with an upwardly opening check valve permitting a free downward

movement of the piston under the influence of 20 gravity, as the shaft is rocked.

8. The combination with a switch operating rock shaft, of an actuator for the shaft, a lateral extension fixed on said shaft, a weight, a flexible element connecting the weight to the 25 rock shaft, a substantially vertical dash pot beneath the rock shaft and having a closed lower end in which the weight is reciprocable as said projection describes an arc beneath the shaft during the rocking movement thereof, said weight having a port therethrough, and a check valve controlling said port to permit the weight to move downwardly in the 30 dash pot by gravity, but checking its upward movement. 35

In witness whereof I affix my signature.

CLARENCE H. BOURGEOIS.
